(57) **CLAIM**

The ornamental design(s) for the square end for a bag, as shown and described.

DESCRIPTION

FIG. 1 is a perspective View of a square end for a bag shown in a closed state showing our new design;

FIG. 2 is perspective view of the square end for a bag shown in an opened state;

FIG. 3 is a top view of the square end for a bag shown in a closed state;

FIG. 4 is a top view of the square end for a bag shown in an opened state;

FIG. 5 is a right side view of the square end for a bag shown in a closed state;

FIG. 6 is a left side view of the square end for a bag shown in a closed state; and,

FIG. 7 is a bottom view of the square end for a bag.

The broken line showing the rest of the remaining bag and stitching is for illustrative purposes only and forms no part of the claimed design.
